UNITED STATES PATENT OFFICE.

HARRY HUNTER COLESTOCK, OF ST. PAUL, MINNESOTA.

SPUTUM-BOX.

1,344,442.

Specification of Letters Patent. Patented June 22, 1920.

Application filed May 5, 1919. Serial No. 294,674.

To all whom it may concern:

Be it known that I, HARRY HUNTER COLESTOCK, a citizen of the United States, residing at St. Paul, in the county of Ramsey and State of Minnesota, have invented a new and useful Sputum-Box, of which the following is a specification.

It appears that the best sputum boxes or cups so far produced, or now in use, are either leaky, spillable or do not otherwise meet the requirements of hygienic safety, convenience or general usefulness, and are intended only for specific uses, for instance, to be carried in the hand or pocket or set upon a table or any handy convenience, none being suitable or hygienically safe to use under cover in bed.

The all-metal mechanically operated and cleanable devices sometimes used, have been condemned, partly because of the risk of contamination and infection in the process of cleansing and disposing of their contents, and partly through the inconvenience and disagreeableness of the necessary act of cleansing.

The foldable, flexible and burnable filler, to be used in a separate metallic case to protect it, has proved not only leakable, hygienically unsafe and obnoxious while in use, but, as well, inconvenient, unsafe to handle and disagreeable in the extreme to take care of, after using, in order to dispose of it.

It is the object of my invention to overcome all these imperfections and provide, first, a burnable water-tight sputum box of simple and rigid construction with an intake opening so located that when in use, and filled nearly half full (its intended safety capacity) it can be tilted at any angle, except face (or intake side) downward, without the contents coming in contact with either the intake opening or close-fitting inclosing lid; and yet can be filled to its entire capacity (when laid on its back) and then tilted at any angle, including face downward, without leakage when lid is closed; second, to provide a protected absorbent pad near intake the purposes of which are (a) to absorb accidentally misdirected sputum; and to fill the function of a cut-off from the lip of sputum when it is inclined to be elastic and adherent as is frequently the case; and (b) if medicated, to disinfect said sputum; third, to provide in a more complete construction, a combined extendible chute

hinged lid and springable flanges that are for the purpose of acting as guards and furnishing another method to secure a water-tight fit as well as side pressure to serve as a stop for lid when closed and, in addition, to produce a desirably resisting action for said lid in opening and closing; fourth, to provide an improved funnel-like intake and trap; fifth, to provide yet more elaborate construction in the incorporation of a hopper frame for the purpose of (a) additionally supporting the face and back walls of box, (b) acting as a guard or trap (so that when sputum has once passed through it it cannot again back up or reenter, or be extracted—even if box is turned upside down with lid open), and (c) a reservoir for the momentary retention (if desired) of a limited amount of sputum for inspection, for instance for traces of blood; sixth, to provide mortises or slots for the reception and guidance of the chute lid side flanges as well as protecting said flanges against sputum retained for inspection as aforesaid; seventh, to provide a sputum box adaptable for all uses including its use under cover in bed; and eighth, to provide a water-proof and water-tight sputum box so constructed out of burnable material that it is complete in itself and self-sufficient for use without the necessity of a separate case or receptacle to protect or carry it about in.

I attain these objects by the mechanism and construction illustrated in the accompanying drawings, in which—

Figure 1 is a broken plan view of the face, or intake, side of box showing the lid opened; Fig. 2 a vertical section of Fig. 1 on the line 2 2, Fig. 1; Fig. 3 a cross-section on the line 3 3, Fig. 1; Fig. 4 a plan view of box (with lid closed) showing a simpler construction than in Figs. 1, 2, 3, 6 and 7; Fig. 5 a vertical section on the line 5 5, Fig. 4 with the addition of dotted lines showing hinge action of lid; Fig. 6 a plan view of box (with lid closed) showing circular shape of a varying form of construction showing a simple form of hopper and trap; Fig. 7 a cross-section on the line 7 7 Fig. 6; Figs. 8, 9 and 10 respectively are face, side and end elevations of lid (illustrated in Figs. 1 and 2) showing the springing tendency of the bended parts; Fig. 11 a plan view of hopper frame independent of box; Fig. 12 a plan view of hopper frame showing an ex-

tension that provides for mortises and a partial bottom to hopper; Fig. 13 a portion of Fig. 7 with the addition of an independent cover and dotted lines showing same removed; Fig. 14 a face elevation of extra cover attached to lid in one form of the construction as shown in Figs. 1 and 2.

Box A, lid B, Bb or Ba, absorbing pad C, funnel D or hopper E pad shield F and support G are the main parts of my invention.

Box A, A' and A'' (as illustrated in Figs. 1, 2, 4, 5, 6 and 7) consists of box, straw or card board or any suitable burnable material and its parts are of water-proof composition or that which is water-proofed in advance of being shaped into parts, or in advance of assembling; or a water-proof bond or cement (for instance paraffin or bees wax) may be used to secure the parts together and at the same time applied in water-proofing exposed surfaces; or water-proofing may be done separately after assembling. The foregoing will apply to all the parts.

The form of construction as illustrated in Figs. 6 and 7 is designed to trap and secure all that can be put into the box and effectually prevent the return of any sputum into the funnel-like entrance (4) after it has once passed through—no matter at what angle the box may be tilted even with the lid open. This is primarily due to the fact of the intake being centrally located. But in Figs. 1, 2 and 3 the intake opening is situated somewhat above the center lengthwise of the box in order to provide extra room in one end (3) so that in emergency occasions when more space is required than is generally the case an excess amount may be accommodated, though said excess amount is liable to reenter the funnel-like intake when tilted, for instance, with the roomiest side up; notwithstanding all of which the box is still secure against leakage or spilling when lid is closed no matter in what position, as aforesaid, the box may be placed.

Lid B (see Figs. 4, 5, 6 and 7) may consist of two pieces of box, straw or card board, (or any suitable material) pasted together or said lid may be pressed into the required shape from a single piece. If of two pieces, as illustrated in Figs. 4 and 5, top piece 20 serves as a projecting cover for that portion of face 1 near opening 4 or for the protection of absorbing pad C (hereinafter described) that is, when pad C is incorporated into the construction. In the process of assembling a portion of piece 20 is cemented to 1, the hinge action being accomplished by previous scoring or grooving at 23. A lifting flap 22 is formed from 20. 21 may consist of wood, cork or any suitable material, or may be the same piece that is punched out of face 1 in producing opening 4, and is preferably slightly tapered or

beveled (cork-like) in order to secure an easy entering and suitably binding fit when closed.

Absorbent pad C, C' and C'' (see Figs. 1, 2, 4 and 6) may consist of blotting paper, 70 and may be suitably medicated, preferably in advance of being formed into shape for assembling, or any suitable powdered or granulated material may be used and shaped into required form by sprinkling onto cement previously applied where pad is to be. The purposes of pad C have been heretofore suggested. 75

Funnel D (in Figs. 6 and 7) is intended to receive sputum and guide it to small opening 80 which is situated in the center of the interior laterally and a little below the center perpendicularly and serves the purpose of an absolute trap against the return of sputum after once having passed through. Figs. 1, 85 2, 3, 8, 9, 10, 12 and 14 represent my invention in its most elaborate construction in which—

Lid Ba (separately illustrated in Figs. 8, 9 and 10) consists of two pieces of any suitable material cemented together, piece 45 preferably box or straw board and piece 40 preferably card board; 40 being so shaped and bent as to form a chute having two springable side flanges 41 and one springable combined flange and lifting flap 42. 41a (see Figs. 2 and 9) is that portion of the chute-flanges 41 that projects rearward and extends beyond the line of the center of the hinge action of lid Ba, the purpose of 41a 100 being to secure 41 in mortises 53 (hereinafter mentioned) even when said lid is opened a greater distance than a right angle. The hinge action at 43 is accomplished in the same manner as described of lid B. 105 Lid Ba is secured to box A' by cementing at its projection 44. Piece 45 is used chiefly for additional strength and to secure flanges 41 and 42 in proper place.

Hopper frame E (see Fig. 11) may consist of a frame (preferably of wood) having sides 50 and ends 51, or in the most elaborate construction, as illustrated in Figs. 1, 3 and 12, an extension 50a is provided that serves, first, as a hygienic guard to flanges 115 41 of lid Ba; second as a guide to opening in partial bottom 52; and third, a hanger for the same (52). By the addition of extension 50a slots or mortises 53 are provided that serve for the reception and securing of chute flanges 41 of lid Ba. The ends 51' of frame E' are of less depth than sides 50', thus leaving an open space (see arrow in Fig. 2) which forms the inlet to box A' and which ends 51' in connection with partial bottom 52 act as a trap the same as described of funnel D in Figs. 6 and 7. 125

Extension cover F (see Figs. 1, 2 and 14) may be attached to lid Ba for the purpose of hygienic protection to absorbing pad C' 130

(that is, when such pad is used in the construction). The attaching of cover F renders unnecessary the flap 42 on lid Ba, therefore 42 is abolished and flap 62 is formed 5 out of a portion of cover F to take its place.

An independent cover Bb (Fig. 13) may be used.

Supports G and G' (Figs. 1, 2, 4 and 5) are used only if necessary to give rigidity to 10 face 1 and back 2.

Parts G, G', and 52 may consist of card, paste board or any suitable material.

I do not restrict my rights to all the detail precisely as herewith set forth and I 15 reserve the privilege of the adoption of any variation (in harmony with the claims here-
to) that my experience and expediency may suggest. For instance, I have selected the detail of construction of box A, as illus-
trated in Figs. 1 and 5 as probably afford-
ing the most practical plan of manufacture
for institutions of limited equipment; but in
manufacturing on a large scale I should pre-
fer to use drawing and forming dies and
25 to form therewith box A out of two pieces
on the order as illustrated in Fig. 7 while
yet retaining the predominantly rectangular
shape of Figs. 1 and 5 but with all edges
rounded as in Fig. 7. And then again, for
30 instance, in cases where a less elaborate and
less expensive construction is required than
shown in Fig. 1, I may eliminate absorbent
pad C and cover F (as shown in Fig. 14)
and use only the cover Ba shown in Figs.
35 8, 9 and 10.

I claim:

1. A water-proof sputum box having a hinged lid and projecting cover, the said lid having a chute with springable side flanges 40 extending into the opening of said box, the said flanges having an extension beyond the

center of the hinge action of the lid, all substantially as described.

2. A water-proof sputum box having a hinged lid and projecting cover, the said lid 45 having a chute with springable side flanges extending into the opening of said box, the said flanges having an extension beyond the center of the hinge action of the lid which also has a frontal combined springable 50 flange and lifting flap, all substantially as set forth.

3. A water-proof sputum box having a hinged lid and projecting cover, the said lid 55 having a chute with springable side flanges extending into the opening of said box, the said flanges having an extension beyond the center of the hinge action of the lid which also has a frontal combined springable flange and lifting flap, all in combination 60 with a combined hopper and trap having mortises to hold the side flanges of said chute, all substantially as set forth.

4. A water-proof sputum box having a hinged lid and projecting cover, the said lid 65 having a chute with springable side flanges extending into the opening of said box, the said flanges having an extension beyond the center of the hinge action of the lid which also has a frontal combined springable 70 flange and lifting flap, all in combination with an absorbent pad located near said opening, and a combined hopper and trap having mortises to hold the side flanges of said chute, all substantially as described. 75

In testimony whereof I have hereunto set my hand this tenth day of February, A. D. 1919.

HARRY HUNTER COLESTOCK.
